UNITED STATES PATENT OFFICE.

JAMES S. CALDWELL, OF KANSAS CITY, MISSOURI.

SPIKED SHOE.

1,087,212.

Specification of Letters Patent. Patented Feb. 17, 1914.

Application filed November 29, 1912. Serial No. 734,061.

To all whom it may concern:

Be it known that I, JAMES S. CALDWELL, a citizen of the United States, residing at Kansas City, in the county of Jackson and State of Missouri, have invented certain new and useful Improvements in Spiked Shoes, of which the following is a specification.

This invention relates to spiked shoes for baseball players and the like, and my object 10 is to produce shoe plates which will enable the wearer to maintain his footing while running in a straight, curved or tortuous course, or in assuming an attitude or position where he is off balance or braced to 15 start suddenly in any direction, and which furthermore will eliminate to a large degree, the chance of injury to a player accidentally struck by the "spikes", as very frequently occurs in the game of baseball where 20 a player slides feet first in an attempt to gain or "steal" a base.

With this general object in view, the invention consists in certain novel and peculiar features of construction and organization as hereinafter described and claimed; 25 and in order that it may be fully understood reference is to be had to the accompanying drawing, in which—

Figure 1, is an inverted plan view of a 30 shoe equipped with plates embodying my invention. Fig. 2, is a side view of the plates and part of the shoe. Fig. 3, is a cross section on the line III—III of Fig. 1.

In the said drawing, 1 indicates a shoe, 35 and secured to the sole thereof by securing devices or rivets 2, is a T-shaped plate 3, arranged with its head extending transversely, and its stem projecting forwardly. Depending from the end of the head adjacent the inner edge of the sole, is a pair of inwardly-converging dull or rounded spikes 4 and 5, and from the opposite end of the head depends a pair of similar inwardly-converging calks or spikes 6 and 7. Preferably spikes 4 and 7 and 5 and 6, extend in 40 parallel planes respectively.

Depending from the front end or extremity of the stem of the plate and extending convergingly rearward is a pair of dull or 45 rounded spikes 8 and 9, spike 8 preferably extending at an angle paralleling that at which the spikes 5 and 6 extend, and spike 9 at an angle paralleling that at which spikes 4 and 7 extend, and depending also 50 from the stem is a dull or rounded spike 10, the same being preferably of slightly greater

height than the other spikes, for a purpose which hereinafter appears.

The plate described may be of any suitable material and may be cast or stamped 60 from sheet metal, in which latter case the various spikes described will be hollow and yet possess the requisite strength and rigidity.

A plate of substantially the same type and 65 numbered 11, is secured to the heel of the shoe, though it is to be understood in this connection, that the arrangement and relation of the spikes on the heel plate is unimportant as any spikes depending from the heel, which will give a firm grip upon the 70 ground may be used, it being desirable, however, that the spikes of the heel plate shall be dull or rounded to minimize chance of injury to any one with whom they may come 75 in more or less forcible contact.

When the wearer is standing at rest, most 80 of his weight is imposed on the spikes of the heel plate and spikes 4 and 6 of the sole plate which latter spikes will be slightly embedded in the ground. In the event he makes ready to start forward and hence leans slightly in that direction, his weight is removed from the heel plate and is imposed mainly on spikes 4 to 7 inclusive, and spike 85 10, and as he starts to run, the center of gravity is shifted further forward and the spikes 8 to 10 inclusive, constitute the supports and resistance points. In the event the wearer makes ready to start sidewise, or 90 is standing in such position that his bracing foot is disposed crosswise of the direction in which he expects to run, the weight is largely imposed on the spikes 4 and 5, or if he leans forward, on the spikes 5, 8 and 10. 95 In reaching overhead with both hands, as in catching an overhead fly ball, one foot is usually thrown forward as a brace, and in this case the spikes 4 and 5 of the advanced foot will constitute the chief points of resistance to slippage. 100

It will be seen that any movement which 105 will remove the weight from the heel will by reason of the increased height of the spike 10, effect the embedment of the same in the ground at the same time that spikes 5 and 7 are embedded, and that the length of said spike 10 also permits it to coöperate with spikes 5 and 8 at times and spikes 8 and 9 at times.

If the spike 10 was of the same length as 110 spikes 5 to 8, it would not be embedded in

the ground with said spikes 5 and 8, for instance, when the foot was occupying a position in which to apply a rearward and lateral thrust to enable the wearer to make a 5 quick start.

In practically every position which the plate occupies when the wearer is in motion, or is poised for a quick start in any direction, one or more of the embedded spikes 10 tends at an angle to the direction in which the movement will occur.

From the above description it will be apparent that I have produced a spiked shoe 15 embodying the features of advantage enumerated as desirable and I wish it to be understood that while I have illustrated and described the preferred embodiment of the same, I reserve the right to make all changes properly falling within the principle of the 20 invention as defined by the appended claims.

I claim:

1. An anti-slipping device, comprising a plate adapted to be secured to a sole and 25 provided with a pair of rearwardly-converging calks for location near the ball portion of the sole near the side margins thereof, and with a longitudinally extending calk in advance of said pair of calks to be positioned 30 midway between the sides of the sole.

2. In an anti-slipping device, a plate adapted to be secured to a sole and carrying a pair of rearwardly converging calks for 35 location at the ball line of the sole, a pair of forwardly diverging calks for location near the toe of the sole, and a calk between said pairs of calks to be positioned midway between the sides of the sole.

3. In an anti-slipping device, a sole having 40 a plate attached thereto, said plate being provided with a pair of forwardly diverging calks spaced slightly from the toe end of the sole and with a calk at the rear of said pair of calks positioned midway between the sides of the sole.

4. An anti-slipping device, comprising a 45 T-shaped plate adapted to be secured to a sole with its head extending transversely and its stem projecting forwardly, a pair of 50 inwardly converging depending spikes at each end of the head of said plate, a pair of rearwardly-converging depending spikes at the front end of the stem, and a longitudi-

nally extending spike depending from the stem. 55

5. In an anti-slipping device, a plate adapted to be secured to a sole and having a pair of rearwardly diverging calks adapted to be located beneath the ball portion of the sole near the margins thereof, a 60 pair of forwardly diverging calks for the toe of the sole, and a calk between said pairs of calks to be positioned midway between the sides of the sole and of greater height than the other calks. 65

6. An antislipping device comprising a plate adapted to be secured to a sole and provided with a pair of forwardly diverging calks for location near the toe end of the sole, a pair of outwardly diverging calks 70 for location beneath the ball portion of the sole near one side thereof, and a calk intermediate said pairs of calks to be positioned midway between the sides of the sole.

7. In an anti-slipping device, a plate 75 adapted to be secured to a sole and provided with a pair of outwardly diverging calks for location beneath the ball portion of the sole near the side thereof, and with a longitudinally extending calk in advance of 80 said pair of calks to be positioned midway between the sides of the sole.

8. An anti-slipping device comprising a plate adapted to be secured to a sole and provided with a pair of rearwardly-diverg- 85 ing calks for location near the ball portion of the sole near the side margins thereof, and with a longitudinally extending calk in advance of said pair of calks to be positioned midway between the sides of the sole. 90

9. In an anti-slipping device, a sole having a set of three calks secured thereto, one of said calks being disposed longitudinally of the sole midway between the sides thereof, and the other calks being juxtaposed 95 near the margin of the sole on the same side of the longitudinal axis thereof and extending in an outwardly diverging relation toward the adjacent sole edge.

In testimony whereof I affix my signature, in the presence of two witnesses.

JAMES S. CALDWELL.
